US0D1097280S

(12) **United States Design Patent** (10) **Patent No.:** **US D1,097,280 S**
(45) **Date of Patent:** **** Oct. 7, 2025**

(54) **CHANDELIER**

(71) Applicant: **Williams-Sonoma, Inc.**, San Francisco, CA (US)

(72) Inventor: **Rachel Kaufman**, San Rafael, CA (US)

(73) Assignee: **Williams-Sonoma, Inc.**, San Francisco, CA (US)

(**) Term: **15 Years**

(21) Appl. No.: **29/913,365**

(22) Filed: **Sep. 29, 2023**

(51) LOC (15) Cl. **26-05**

(52) U.S. Cl.

USPC **D26/86**

(57) **CLAIM**

The ornamental design for a chandelier as shown and described.

DESCRIPTION

FIG. 1 is a top perspective view of the chandelier;

FIG. 2 is a front elevational view of the chandelier;

FIG. 3 is a rear elevational view of the chandelier;

FIG. 4 is a left side elevational view of the chandelier;

FIG. 5 is a right side elevational view of the chandelier;

FIG. 6 is a top plan view of the chandelier; and,

FIG. 7 is a bottom plan view of the chandelier.

The broken line portions of the drawings are included to show portions of the chandelier that form no part of the claimed design.

1 Claim, 7 Drawing Sheets
